GUN MOUNTING

Edward Arthur Beckton Rice, Newton Abbot, and Alfred German Rose and Sidney Curtis, Gainsborough, England; said Rose and said Curtis assignors to Rose Brothers (Gainsborough) Limited, Gainsborough, England, a company of Great Britain

Application October 15, 1941, Serial No. 415,028
In Great Britain October 24, 1940

7 Claims. (Cl. 89—37.5)

1

This invention relates to gun mountings of the type in which the gun or gun assembly is mounted on a carriage arranged for movement along a track.

It is an object of the present invention to provide a gun mounting of this type in which the gun carriage can be quickly moved from one position to another along the track without distracting the attention of the operator from the target and without the need for much exertion on the part of the operator.

According to the present invention, there is provided a gun mounting of the type described wherein the carriage is arranged to be driven along the track by a rotatable driving member mounted in the carriage and engaging the track, driving means being provided on the carriage for bringing about rotation of the driving member, and wherein the starting and stopping of the driving means is controlled by a pair of controlling members one of which is adapted upon operation to cause the driving means to rotate in one direction and the other to cause the driving means to rotate in the opposite direction. Conveniently, the controlling members are adapted for attachment to the hand grip of the gun or gun assembly.

More specifically, the gun mounting according to the invention enables a gun or guns to be swung in azimuth in opposite directions by the manual operation of control means on the gun or guns.

Conveniently, the motor is mounted on the carriage in such a manner that, in the event of failure of the motor to drive the pinion for any reason, e. g. a discharged battery, the motor can be quickly disconnected from the pinion, leaving the carriage free to be moved along the track by hand. Thus, the motor may be carried on a bracket pivoted on the carriage and provided with a spring tending to cause the bracket to swing away from the carriage to disconnect the motor from the pinion, the bracket being normally locked in position against the action of the spring by a spring-loaded locking pin passing through the bracket into the carriage and released by pulling out the pin.

The invention is particularly useful in its application to gun mountings for aircraft, armoured cars and the like, and, by way of example, such an application of the invention will now be described in greater detail, with reference to the accompanying drawings in which:

Figure 1 is a plan view of a gun mounting ac-

2

cording to the invention, shown in position in the fuselage of an aeroplane,

Figure 2 is a part sectional end elevation of the mounting, drawn to a larger scale than Figure 1, as viewed from the right of Figure 1, the carriage being deemed to be in a central position on the track,

Figure 3 is a plan view of the carriage, drawn to a larger scale than Figures 1 and 2, with the upper structure removed,

Figure 4 is a part sectional elevation taken on the line 4—4 in Figure 3, with a portion of the upper structure removed, and

Fig. 5 is a diagram illustrating the construction of the track.

Referring to the drawings, a track generally indicated by reference numeral 11 is mounted in the fuselage 12 of an aeroplane by means of supporting brackets 13, attached to a platform 14 in the fuselage, and a bracket 16 attached to a shield 17 which is itself mounted on the platform 14 by means of a bracket 18. The track 11 consists of a straight portion *a*, extending transversely of the fuselage 12, and two arcuate portions *b* merging into the straight portion *a* and extending towards the front of the aeroplane. The track 11 has a cross-section of channel shape and is disposed with the flanges 19 of the section horizontal and the web 21 of the section on the inside of the track.

Supported on rollers 22 arranged to run on the faces of the flanges 19 is a gun carriage 23 attached to the top of which is a gun supporting pillar 24 which is formed at its upper extremity with a split bearing 26, 27 adapted to carry a gun assembly consisting of a pair of machine guns 28. The portion 26 of the bearing 26, 27 is hinged on the pillar 24 at 29 for easy removal of the gun assembly, a quick-release pin 31 being provided for locking the two parts of the bearing together.

The gun carriage 23 embraces the track 11 and is guided on the track by a pair of rollers 32 and two pairs of rollers 33. The rollers 32 are arranged to bear against the face of the web 21 of the track 11 (see particularly Figure 4), one towards the top of the track and the other towards the bottom, and are freely mounted on a vertical shaft 34 rotatably supported in bearings 36 housed in the upper and lower walls of the carriage. The rollers 33 are arranged to bear against the vertical faces of the flanges 19 of the track 11, the upper pair being freely mounted on studs 37 attached to the upper wall of the carriage 23 at positions one on each side of the

axis of the rollers 32 (considered in the direction of travel of the carriage), while the lower pair are freely mounted on studs 38 attached to the lower wall of the carriage at positions coaxial with the studs 37.

The face of the web 21 of the track 11 and the vertical faces of the flanges 19 of the track thus act as guiding surfaces for the carriage 23 and the width of the track 11, i. e. the distance between the face of the web 21 and the vertical faces of the flanges 19, is such as to provide just sufficient clearance between the track 11 and the rollers 32 and 33 for easy running. It will be understood that the width of the track 11 is greater on the arcuate portions b than on the straight portion a because of the triangular disposition of the rollers 32 and 33 as viewed in plan.

At the junctions of the straight portion a and the arcuate portions b of the track 11, the face of the web 21 is provided with a cam surface 39, the purpose of which is to ensure that the rollers 32 and 33 continue simultaneously to bear on the track 11 during the passage of the carriage 23 from the straight portion a to the arcuate portions b and vice versa.

The construction of the track 11 is shown in Figure 5 and since the arcuate portions b merge into the ends of the straight portion a in an identical manner, it will be sufficient to describe the merging of one of the arcuate portions b into the straight portion a.

The outer surface of the arcuate portion b of the track 11, i. e., the path followed by the vertical faces of the flanges 19, follows an arc struck from a point o until it meets the outer surface of the straight portion a at a point in a line o—o, the line o—o being disposed normal to the straight portion a of the track and passing through the point o. The straight portion a of the track then continues as a tangent to the outer surface of the arcuate portion b. The inner surface of the arcuate portion b of the track 11, i. e., the face of the web 21, also follows an arc struck from the point o until it meets a radial line o—c, and then continues as a compensating cam surface 39 until it meets the inner surface of the straight portion a at a point in a line d—d running parallel with the line o—o. The inner surface of the straight portion a then continues on a path parallel to that followed by the outer face of the straight portion a.

It will thus be seen that the compensating cam surface 39 extends on each side of the line o—o. The length of the cam surface 39 and its disposition in relation to the line o—o depends on the relative dispositions of the roller 32 and the rollers 33. Thus, assuming the carriage 23 to be moving from left to right, it will be seen from the two positions of the carriage 23 shown in Figure 5, that the cam surface 39 extends to the left of line o—o by an amount such that when the centre of the forward roller 33 lies on the line o—o, and the roller is thus at the junction of the straight and arcuate portions of the track 11, the centre of the roller 32 lies on the line d—d and is thus about to come under the influence of the cam surface 39. The carriage 23 is shown in this position by full lines. The full length of the cam surface 39 is such that when the centre of the rearward roller 33 lies on the line o—o, and the carriage as a whole is thus about to move on to the arcuate portion b of the track, the centre of the roller 32 lies on the radial line o—c and is thus about to leave the cam surface 39. The

carriage 23 is shown in this position by chain-dotted lines. The profile of the cam surface 39 is such that the rollers 33 and the roller 32 continue simultaneously to bear on the track 11 during the passage of the carriage 23 from the straight portion a to the arcuate portion b and vice versa.

With this construction, the rollers 33 and the roller 32 are disposed so as to provide rigid support for the carriage at any position on the track while, at the same time, the carriage can be freely moved along the track.

Secured to the central grooved portion of the shaft 34 is a pinion 41 arranged to mesh with a rack 42 secured to the central portion of the web 21 of the track 11. The portions of the rack corresponding to the straight portion a and the arcuate portions b of the track 11 each have teeth of a standard form except on the portions corresponding to the cam surfaces 39 where, it will be understood, the teeth have to be slightly modified in shape so as to allow smooth operation between the rack 42 and the pinion 41 during the passage of the carriage from the arcuate portions b to the straight portion a and vice versa.

The shaft 34 protrudes through the bottom wall of the carriage 23 and has secured to its protruding grooved end a driving flange 43 which is arranged to be driven by an annular wormwheel 44 through a pair of flanged gripper members 45 in a manner which will be described later. The wormwheel 44 is arranged to be driven by a worm 46 secured to a shaft 47 supported in bearings 48 carried by a bracket 49 pivotally attached at 50 to a bracket 51 secured to the carriage 23. Stops 52, having inclined abutment surfaces, are formed on the bracket 49 to prevent excessive pivotal movement thereof, the abutment surfaces normally being clear of the carriage 23 by an amount sufficient to allow adequate pivotal movement of the bracket 49. The worm 46 is driven from an electric motor 53, attached to the bracket 49 through gears 54, 55 and 56, the gear 54 being secured to the armature shaft 57 of the motor 53, the gear 55 being freely mounted on a stud 58 carried by the bracket 49 and the gear 56 being secured to the worm shaft 47.

The annular wormwheel 44 is formed with an internal surface which tapers from a maximum diameter at the outside edges of the annulus to a minimum diameter midway in the width of the annulus (see Figure 4), and is supported on the flanged gripper members 45 the flanges of which are shaped so as to mate with the internal surface of the wormwheel 44. The gripper members 45 are squeezed towards each other to grip the internal surface of the wormwheel 44 by a series of springs 59 supported on studs 61 passing freely through the gripper members 45 and the driving flange 43. The upper gripper member 45 is secured to the driving flange 43 by a series of driving bolts 62 the heads of which pass through the lower gripper member 45. The pressure exerted by the springs 59 is adjustable by means of nuts 63 for the purpose of varying the gripping pressure between the gripper members 45 and the wormwheel 44.

With the above construction, it will be seen that the wormwheel 44 and the gripper members 45 constitute a slipping clutch mechanism which will prevent damage to the apparatus in the event that the motor 53 is kept running long enough to cause the carriage 23 to strike the supporting brackets 13 at the ends of the track 11, the wormwheel 44, in such an event, merely slipping round

the gripper members 45 against the action of the springs 59.

As mentioned above, the bracket 49 is pivoted at 50 and carries the motor 53 with its gear 54, the intermediate gear 55, and the worm 46 with its gear 56. It will be seen, therefore, that when the bracket 49 is swung away from the carriage 23 the worm 46 is caused to disengage from the wormwheel 44 and thus disconnect the drive from the motor 53 to the pinion 41. A leaf spring 66 is attached to the carriage 23 and is caused to exert a spring pressure against the bracket 49 when it is in the operative position, as shown in Figure 4, so that the bracket 49 is continuously urged to swing outwardly.

In order to lock the bracket 49 in its operative position against the action of the spring 66, there is provided a plunger 67 which is housed in a bearing 68 attached to a lug 69 extending from the bracket 49 and lying adjacent an end of the vertical wall of the carriage. The plunger 67 passes through the lug 69 into a recess 71 in the carriage and the bearing 68 is formed with a recess 72 for the accommodation of a spring 73 disposed around the shank 74 of the plunger 67 and bearing at one end against the plunger 67 and at the other end against the base of the recess 72. The shank 74 protrudes through the bearing 68 and has secured to its end by means of a pin 76 a knob 77 in which is secured a pin 78 to facilitate handling.

In order to counteract any twisting moment in the carriage 23 arising from the disposition of the motor 53 and its associated gearing in relation to the track 11, there is secured to the lower wall of the carriage 23 an arm 79, suitably recessed for the accommodation of the wormwheel 44 and its associated parts, provided at its extremity remote from the carriage 23 with a roller 81 freely mounted on a stud 82 secured to the arm 79, the roller 81 being arranged to bear against an auxiliary track 83 secured to the platform 14 by means of bolts 84.

The motor 53 is of the reversible type and is connected to an electric battery (not shown) through a pair of contactor starters (not shown) and a pair of thumb switches 86 and 87 attached one to the hand grip of each of the pair of machine guns 28, the electrical connections being such that the switch 86 causes the motor 53 to rotate in the direction necessary to drive the carriage 23 from right to left (as viewed in Figure 1) and the switch 87 causes the motor to rotate in the opposite direction to drive the carriage from left to right.

It will be seen that, to move the carriage 23 from one position to another on the track 11, it is only necessary for the operator to depress one or the other of the switches 86 or 87, depending on the direction in which it is desired to move the carriage, whereupon the motor 53 is caused to rotate in the appropriate direction and drives the pinion 41 through the gears 54, 55 and 56, the worm 46 and the wormwheel 44, the pinion 41, in turn, rolling along the rack 42 to drive the carriage 23 along the track 11.

The pivotal mounting of the bracket 49 allows the drive to the pinion 41 to be disconnected at will so that, should the necessity arise, the carriage 23 can be freed for movement along the track 11 by hand operation. Thus, in the event of failure of the motor 53 to drive the pinion 41 for any reason, it is only necessary for the operator to withdraw the knob 77 against the action of the spring 73 until the plunger 67 is clear of

the recess 71 in the carriage 23, whereupon the bracket 49, together with the motor 53 and its associated gearing, is caused to swing outwardly under the action of the spring 66 to disconnect the worm 46 from the wormwheel 44. The carriage 23 is then free to be moved along the track by hand. When the mounting is being used in this manner, the carriage 23 may be locked at any given position along the track 11 by pushing the bracket 49 towards the carriage until the plunger 67 snaps back into locking position when the worm 46 by its engagement with the wormwheel 44 effectively locks the carriage against movement along the track. A hand knob 88 is attached to the armature shaft 57 of the motor at the opposite end to the gear 54 for the purpose of turning the armature shaft slightly in case the worm 46 does not properly engage the wormwheel 44 when the bracket 49 is swung back into operative position.

We claim:

1. A gun mounting comprising a track, a gun carriage movably supported on the track and arranged to carry a pair of guns, means on said carriage for guiding it along the track, the track being formed with a rack extending along its length, a rotatable pinion mounted in said carriage and arranged to engage the rack, a reversible electric motor mounted on said carriage in driving connection with said pinion, said motor being carried on a bracket pivoted on said carriage, spring means tending to cause said bracket to swing away from said carriage so as to disconnect said motor from said pinion, a spring-loaded locking pin arranged to pass through said bracket into said carriage so as to lock said bracket in its operative position against the action of said spring means, and a pair of switches arranged to connect said motor with a source of electric power, e. g., a battery, in such a manner that one switch is capable of bringing about rotation of said motor in one direction and the other is capable of bringing about rotation of said motor in the opposite direction, said switches being adapted for attachment one to the hand grip of each of said guns.

2. A gun mounting comprising a track of the kind in which portions having different paths merge into each other, said track being formed with two opposing carriage-guiding surfaces, a gun carriage movably supported on said track and arranged to engage said guiding surfaces at at least three points simultaneously, at least two of said points being on one of said surfaces and the remaining point or points being on the opposing surface, at least one of said surfaces being formed on at least one merging portion of the track with at least one compensating cam surface against which a surface-contacting point on said carriage bears, during passage of said carriage over said merging portion of said track, to cause said carriage to continue to bear on said track at said points.

3. A gun mounting comprising a track the path of which comprises a straight portion and a curved portion merging into each other, said track being formed with opposing outer and inner carriage-guiding surfaces, a gun carriage movably supported on said track and arranged to carry a pair of guns, guiding means on said carriage arranged to engage said surfaces at three points simultaneously for guiding said carriage along said track, two of said points being on said outer surface and the remaining point being on said inner surface, said inner surface being pro-

vided on the merging portion of said track with a compensating cam surface against which one of the carriage-guiding means is arranged to bear during passage of said carriage over said portion of said track to cause said carriage to continue to bear at said three points, a rack extending along the length of said track, and a rotatable pinion mounted in said carriage and arranged to engage said rack.

4. A gun mounting including a track, a gun carriage having guided movement on said track, driven means on said carriage contacting said track to cause the movement of the carriage, a bracket connected with said carriage for movement to an active position or an inactive position, and driving means on said bracket which cooperates with said driven means to drive the latter to move the carriage when the bracket is in the active position, said driving means being disengaged from said driven means when the bracket is in its inactive position.

5. A gun mounting including a track, a gun carriage constructed and arranged to move along said track, rollers on said carriage rotatable on vertical axes respectively in rolling contact with opposite sides respectively of said track, other rollers on said carriage rotatable on horizontal axes respectively in rolling contact with upper surfaces of said track respectively, a driven shaft providing the axle for certain of said rollers, and means on the shaft which coacts with means on

the track to cause the movement of said carriage along the track.

6. A gun mounting comprising a track, a gun carriage movably supported on the track, means on said carriage for guiding it along the track, a rotatable driving member mounted in said carriage and arranged to engage the track so as to cause said carriage to move along the track, driving means mounted on said carriage and arranged to bring about rotation of said driving member, said driving means being carried on a bracket pivoted on said carriage, spring means tending to cause said bracket to swing away from the carriage, so as to disconnect the driving means from the driving member, means for maintaining said bracket in the driving position, means for releasing said bracket so as to allow it to swing away from the carriage under the influence of the spring, and a pair of controlling members in connection with said driving means, one of the controlling members being arranged upon operation to cause the driving means to rotate in one direction and the other to cause the driving means to rotate in the opposition direction.

7. A gun mounting according to claim 6, including a fixed stop arranged to limit the extent of the pivotal movement of said bracket under the influence of said spring.

EDWARD ARTHUR BECKTON RICE.
